UNITED STATES PATENT OFFICE.

FERNAND E. D'HUMY, OF ENGLEWOOD, NEW JERSEY, ASSIGNOR TO RAMP BUILDINGS CORPORATION, OF NEW YORK, N. Y., A CORPORATION OF DELAWARE.

STORAGE BUILDING.

Application filed July 8, 1925. Serial No. 42,207.

This invention relates to improvements in building structures, and more particularly to storage buildings, the improvements being especially applicable to garage structures for 5 storing motor vehicles.

One object of the invention is to provide a storage building so constructed that vehicles may travel under their own power from floor to floor of the building to and 10 from storage spaces on the various floors.

Another object of the invention is to provide a storage building having a plurality of groups of floors, the floors of two or more groups being arranged in horizontal planes 15 intermediate the floors of another group, the floors of one group being connected to the floors of the next higher and next lower group by inclined ramps or driveways. In a structure arranged as described vehicles 20 passing from one floor of one group to the next floor of the same group must pass over one floor of each of the other groups and over the ramps or inclined driveways connecting said floors.

25 Another object of the invention is to provide a storage building having a plurality of groups of floors with the floors of two or more groups arranged in horizontal planes between the horizontal planes of the floors 30 of each group whereby all of said floors may be connected together by short slightly inclined ramps or driveways. In a building constructed as described motor vehicles may pass from one floor to any other floor in any 35 of the groups over short and slightly inclined driveways and the waste of storage space due to the ramps or driveways will be reduced to a minimum.

40 Another object of the invention is to surround the floors of each group with walls and to arrange the ramps to pass through the interior dividing walls between the groups of floors.

45 There are other important objects of the invention which will appear hereinafter.

In the drawings:

Fig. 1 is a horizontal sectional view of a building embodying the invention;

50 Fig. 2 a vertical sectional view thereof taken on the line 2—2 of Fig. 1;

Fig. 3 a vertical sectional view taken on the line 3—3 of Fig. 1;

Fig. 4 a vertical sectional view taken on the line 4—4 of Fig. 1;

Fig. 5 a horizontal sectional view similar 55 to Fig. 1 showing a modified form of invention;

Fig. 6 a vertical sectional view taken on the line 6—6 of Fig. 5;

Fig. 7 a vertical sectional view taken on 60 the line 7—7 of Fig. 5; and

Fig. 8 a vertical sectional view taken on the line 8—8 of Fig. 5.

Referring to Figs. 1 to 4 inclusive, 1 designates the outer walls of the building. A, B 65 and C designate three groups of floors arranged within the outer walls of the building. The floors of group A are separated from the floors of groups B and C by a vertical dividing wall 2 and the floors of group 70 B are separated from the floors of group C by the vertical dividing wall 3. The outer walls 1 are provided with suitable window openings 4 and with a suitable doorway 5 giving access to the ground floor of group 75 A of floors. In the construction shown the lowermost floor of group A is arranged as the ground floor of the garage and the entrance 5 leads into said ground floor. It will, of course, be understood that the floor of the 80 garage may be the lowermost floor of any one of the groups.

The groups B and C of floors are arranged at different levels and in horizontal planes which lie between the floors of group A. 85 This is clearly shown in Fig. 2. The floors of group B are lower than the floors of group C and short ramps 6 are arranged to connect the floors of group A with the next floors of group B. These ramps extend 90 through the dividing wall 2, as shown clearly in Fig. 1. The floors of group B are connected to the next higher floors of group C by short inclined ramps or driveways 7. These ramps extend through the dividing 95 wall 3. The ramps 7 preferably extend the full width of the floors B and C and those portions of said inclined driveways adjacent the dividing wall 3 may be used for car storage purposes, as shown clearly in Fig. 1. 100

The floors of group C are connected to the next higher floors of group A by inclined ramps 8. These ramps extend through the dividing wall 2.

105 Each of the floors A, B and C has an unobstructed passage or driveway running throughout the length of the floor and connecting the ramps, the ramps leading di-

rectly into these driveways. The storage spaces on each floor may be sub-divided in any suitable manner, either by low partitions or rails 9 or by suitable markings 8 on the floors and walls.

With the construction heretofore described a car will enter on the first floor of group A and move to ramp 6 connecting said floor with the next floor above in group B. From 10 the first floor of group B the car will move up ramp 7 to the first floor of group C and then from group C it will pass up ramp 8 to the second floor of group A, and so on throughout the various floors of the building. The ramps connecting the floors of the various groups are short and of slight inclination so that the car may move up 15 through the building over an easy grade with an ample horizontal floor space between 20 adjacent ramps.

The ramps 7 are made as broad as the two groups of floors which they connect in order that the side portions thereof adjacent the dividing wall may be used for storage 25 purposes. The grade of this ramp is comparatively slight and for that reason the side portions thereof may be conveniently used for storage purposes and there will be no lost or dead space.

30 In Figs. 5 to 8 inclusive a slightly different form of building is shown. In these views four groups of floors, D, E, F and G are shown. The horizontal planes of the floors of groups E, F and G are arranged 35 between the planes of the floors of group D. The planes of any three groups of floors are arranged between the floors of the other group, that is to say, the planes of the floors of groups D, F and G are arranged between 40 the planes of the floors of group E. The groups of floors D and E are separated from the groups F and G by a vertical dividing wall 10. The floors of group D are separated from the floors of group E by a dividing 45 wall 11 while the floors of group F are separated from the floors of group G by a dividing wall 12. The floors of group D are connected to the floors of group E by inclined ramps or driveways 13 which extend 50 through the dividing wall 11. These ramps are as broad as the floors of the groups which they connect and extend from the outer wall 1 of the building to the dividing wall 10. Those portions of these inclined 55 ramps which are adjacent the dividing wall 11 may be used for storage purposes so that those parts of the ramps which adjoin the dividing wall are not waste or dead spaces. The floors of group E are connected to the 60 next higher floors of group F by a series of ramps 14. These ramps extend through the dividing wall 10. The floors of group F are connected to the next higher floors of group G by ramps 15. These ramps extend through 65 the dividing wall 12 and are equal in width

to the width of the floors which they connect. The side portions of these ramps adjacent the dividing wall 12 may be used for storage purposes. The floors of group G are connected to the next higher floors of group D 70 by a series of ramps 16, these ramps extending through the dividing wall 10. Each floor is formed with a broad passage through which the vehicles may pass from one ramp to the next ramp and storage spaces for cars 75 are arranged along the walls. The building is provided with the usual window openings and with an entrance 17 leading to the lowermost floor of group D, said floor being the ground floor of the garage. From this 80 ground floor the cars pass up the first ramp 13 to the lowermost floor of group E. From this floor they may pass up the first ramp 14 of the series to the first floor of group F. From the first floor of group F the cars 85 may pass up ramp 15 to the first floor of group G and then up ramp 16 to the second floor of group D, and so on up through the building.

What I claim is:

1. A building structure comprising outer walls, a plurality of groups of superposed floors within said outer walls each group overlying a part of the ground area within the outer walls, the floors of a plurality of groups being arranged in horizontal planes lying between the horizontal planes of the floors of another group, vertical dividing walls separating the floors of one group from the floors of the adjoining group, and inclined ramps or driveways connecting the floors of each group to the floors of the next higher group, said ramps extending through the said dividing walls.

2. A building structure comprising outer walls, a plurality of groups of superposed floors within the said outer walls each group overlying a part of the ground area within the outer walls, the floors of a plurality of groups being arranged in horizontal planes 95 lying between the horizontal planes of the floors of another group, inclined ramps or driveways connecting the floors of each group to the floors of the next higher group, the ramps connecting two groups of floors 100 being as wide as the floors which they connect and the side portions of said ramps forming storage spaces, and vertical dividing walls extending inwardly over the storage portions of the said wide inclined ramps.

3. A building structure comprising outer walls, a plurality of groups of superposed floors within the said outer walls, the floors of one group being arranged in horizontal planes out of the horizontal planes of the floors of the other group, inclined ramps or driveways connecting the floors of one group with the floors of the other group, said ramps being as wide as the connected floors 125 and the side portions of said ramps forming 130

storage spaces, and vertical dividing walls extending inwardly over the storage portions of the said wide inclined ramps.

4. A building structure comprising a group of horizontal superposed main floors at one side of a vertical dividing plane and extending the length thereof; two groups of horizontal superposed storage floors at the opposite side of said plane and extending therealong the floors of one of said groups being at staggered levels with relation to the floors of the other group and a floor of each of said groups being located between the levels of each pair of main floors; two groups of superposed oppositely inclined transverse ramps extending through said vertical plane at widely spaced points and connecting the floors of the spaced groups to the main floors; and a group of superposed longitudinally inclined floors extending along the said vertical wall and located between the transverse ramps, said inclined floors connecting together the floors of the spaced groups, and one of said inclined floors being arranged between each pair of main floors, each main floor having a longitudinal driveway space connecting the ends of the transverse ramps leading to it, and each longitudinally extending inclined floor and its connected horizontal floors having a longitudinal driveway space connecting the opposite ends of the transverse ramps with storage spaces along it, the driveways on opposite sides of the dividing plane being parallel with each other and with the said plane whereby a horizontal driveway space is provided at each end of each ramp and at each end of each inclined floor.
5. A building structure comprising a group of horizontal superposed main floors at one side of a vertical dividing wall and extending the length thereof; two groups of horizontal superposed storage floors at the opposite side of said wall and extending therealong the floors of one of said groups being at staggered levels with relation to the floors of the other group and a floor of each of said groups being located between the levels of each pair of main floors; two groups of superposed oppositely inclined transverse ramps extending through said vertical wall at widely spaced points and connecting the floors of the spaced groups to the main floors; and a group of superposed longitudinally inclined floors extending along the said vertical wall and located between the transverse ramps, said inclined floors connecting together the floors of the spaced groups, and one of said inclined floors being arranged between each pair of main floors, each main floor having a longitudinal driveway space connecting the ends of the transverse ramps leading to it, and each longitudinally extending inclined floor and its connected horizontal floors having a longitudinal driveway space connecting the opposite ends of the transverse ramps with storage spaces along it, the driveways on opposite sides of the dividing plane being parallel with each other and with the said plane whereby a horizontal driveway space is provided at each end of each ramp and at each end of each inclined floor.

In testimony whereof I hereunto affix my signature.

FERNAND E. D'HUMY.
